UNITED STATES PATENT OFFICE.

JOSEPH LAWTON DIXON, OF DETROIT, MICHIGAN.

ELECTRIC FURNACE.

1,198,625.

Specification of Letters Patent. Patented Sept. 19, 1916.

Original application filed February 23, 1915, Serial No. 9,732. Divided and this application filed April 16, 1916. Serial No. 30,002.

To all whom it may concern:

Be it known that I, JOSEPH L. DIXON, a subject of the King of Great Britain, residing in the city of Detroit and State of Michigan, have invented certain new and useful Improvements in Electric Furnaces, and do hereby declare the following to be a full, clear, and exact description of the invention, such as will enable others skilled 10 in the art to which it appertains to make and use the same.

My present invention relates to that class of electric smelting furnaces wherein the current may be made to pass either from 15 one electrode to another over the bath or from one or more of these either wholly or in part through the bath and furnace lining.

The object of my invention is to supply 20 an improved construction for electric smelting furnaces of this kind whereby three-phase currents fed from specially arranged transformers are made controllable as to their phase relations by suitable switches, so as to cause different proportions of the total 25 current to flow through the bath and lining.

It is a further object of the invention to 30 so accomplish this that a maximum of flexibility in such current changes may be attained, and to do this without unbalancing the load on the feeding mains.

A preferred embodiment of the invention is illustrated diagrammatically in the accompanying drawings wherein—

Figure 1 shows a furnace having two 35 groups of three upper electrodes supplied with three-phase alternating current and Figs. 2 and 3 are vector diagrams illustrating different phase conditions produced by certain changes in the electric connections 40 shown in Fig. 1.

In Fig. 1, the usual hearth, crucible or container is shown at 10, the molten bath within it is shown at 11 while the six upper electrodes 12, 13, 14, 15, 16 and 17 project 45 downward toward the bath through the insulating cover 18. The current which passes downward through the bath, when so desired returns through the lower electrode 19. The working current is derived from the three-phase alternating current mains, 20, 21 and 22 through two groups of three transformers shown respectively at 23, 24 and 25 and at 26, 27 and 28. The three primaries of the 50 transformers 23, 24 and 25 are connected in

triangular connection with the leads or 55 mains 20, 21 and 22; while the remaining three transformers 26, 27 and 28 are connected in star fashion. A common conductor 29 leads to the lower electrode 19, and to this one is connected one terminal of each 60 of the secondaries of all the transformers. The remaining secondary terminal of each transformer is connected to its appropriate upper terminal, as shown.

While I have shown one three-trans- 65 former group fed by triangularly connected conductors and one such group combined therewith as described and fed by star-con- nected conductors, it is to be understood that my invention is not limited to the use 70 of a single group of each kind but covers combinations of triple groups of these two kinds whether one or more of each of such groups is used.

As shown in Fig. 1, the connection to the 75 two triple groups are commanded by the two multiple switches 30 and 31. These act, in the triangularly-connected group of 80 transformers, to reverse the terminal connections of one primary coil of the three 85 with respect to two of the main leads, all other terminal connections remaining permanent. In the star connected group these 90 switches act to reverse the terminal connections of one of the primary coils with respect to the interior or common connection of the star. These switches are examples of what may be used in this manner in my system, and other modes of changing connections may be used for altering the phase 95 relations without departing from my invention.

When the switches 31 are closed and 100 switches 30 are open the phase relations shown in Fig. 2 are obtained. In this case, 95 assuming the currents to be equal in all of the upper electrodes, the value of the current through the bath will be zero. When, on the other hand, switch 31 is open and switch 30 is closed, the phase relations will 105 be as indicated in Fig. 3. In this case, as- suming currents of equal unit magnitudes in the upper electrodes, the value of the current through the bath will be 1.04. Other possible arrangements will be obvi- 110 ous, and by increasing the number of switches, a greater number of different phase 115 relations are made available, by choice of

which various proportions of current flow may be made to reach the lower electrode through the bath.

By using two groups of transformers, one connected to the supply mains in triangular and the other in star fashion the proportion of current which may be caused to flow through the bath to the electrode can be much more extensively varied than would be possible if the electrodes were fed from groups of transformers delivering three-phase star-connected currents in the ordinary manner. In such ordinary cases, the only changes available are those brought about by the reversal of one phase, which, in the case of a furnace with six upper electrodes causes the current in the lower electrode to be four times as great as that in each of the upper electrodes.

20 This application is a division of my earlier application for improvement in electric furnaces, filed February 23, 1915, Serial No. 9782.

What I claim is:

- 25 1. An electric furnace having a lower electrode and two or more groups of three upper electrodes, main leads for supplying three-phase alternating current, transformers in groups of three corresponding in number 30 with said upper electrodes, and having their secondary coils suitably connected with said upper and lower electrodes, conductors connecting the primaries of one or more of said three-transformer groups with said main leads in triangular fashion, and conductors connecting the remaining primary groups in star fashion.
2. An electric furnace having a lower electrode and two or more groups of three 40 upper electrodes, main leads for supplying three-phase alternating current, transformers in groups of three corresponding in number with said upper electrodes, and having one terminal of each secondary connected to one of said upper electrodes while the other secondary terminals are connected in common to said lower electrode, con-

ductors connecting the primaries of one or more of said three-transformer groups to said main leads in triangular fashion, and 50 conductors connecting the remaining primary groups in star fashion.

3. In a heating equipment for electric furnaces, main leads for supplying three-phase alternating current, one or more 55 groups of three transformers having their primary coils connected to said leads in triangular fashion, one or more similar groups connected with said main leads in star-fashion, and suitable switches arranged 60 to reverse the terminal connections of one primary in each triangularly connected group with relation to two of said main leads.

4. In a heating equipment for electric furnaces, main leads for supplying three-phase 65 alternating current, one or more groups of three transformers having their primary coils connected to said leads in triangular fashion, one or more similar groups connected with said main leads in star fashion, 70 and suitable switches arranged to reverse the terminal connections of one primary in each star connected group with respect to the interior or common connection of the star.

75 4. In a heating equipment for electric furnaces, main leads for supplying three-phase alternating current, one or more groups of three transformers having their primary coils connected to said leads in triangular 80 fashion, one or more similar groups connected with said main leads in star fashion, and two or more sets of multiple switches arranged to reverse the terminal connections of one primary in each triangularly 85 connected group with relation to two of said main leads, while also reversing the terminal connections of one primary in each star connected group with respect to the interior or common connection of the 90 star.

In testimony whereof, I have affixed my signature.

JOSEPH LAWTON DIXON.
